UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

GRAIN AND MERCHANDISE CAR.

Application filed January 13, 1923. Serial No. 313,328.

To all whom it may concern:

Be it known that I, ARGYLE CAMPBELL, a citizen of the United States, residing at Chicago, in the county of Cook and State 5 of Illinois, have invented a certain new and useful Improvement in Grain and Merchandise Cars, of which the following is a full, clear, concise, and exact description, reference being had to the accompanying drawings, forming a part of this specification.

My invention relates to improvements in grain and merchandise cars and more particularly to the construction of the doors and framework identified therewith.

An object of the invention is to provide doors on the exterior of the car which will safely hold grain or similar granular material loaded in direct contact with the doors and without interior grain doors or boarding such as are now commonly used.

Another object of the invention is to secure a closure which will prevent leakage of pulverulent or granular lading and which shall fully protect the lading against the 25 entry of snow, rain or the like.

A further object of the invention is to utilize the weight of the closure itself and the outward thrust of the lading against the closure for the purpose of securing a tight 30 joint between the car framing and the closure or between sectional parts of the closure.

A more specific object of the invention is to provide suitable means for moving the 35 closure and overcoming the frictional resistance between the lading and the inner face of the closure.

Other objects of the invention will more clearly appear from the description considered in connection with the drawings, 40 hereinafter following.

In the drawings forming a part of this specification, Figure 1 is a side elevation of a portion of a car showing my improvements in connection therewith. Figure 2 is 45 a vertical sectional view taken on the line 2-2 of Figure 1. Figure 3 is a perspective detail view showing the relation between the sealing member and closure sections and is

taken on a line corresponding to line 3-3 of Figure 1. Figure 4 is a detail perspective view of one of the rear margins of the closure in its relation to the door post and is taken on a line corresponding to line 4-4 of Figure 1. Figure 5 is a detail perspective view of the bottom of the door in its relation to the car structure and is taken on a line corresponding to line 5-5 of Figure 1. Figure 6 is a horizontal sectional view taken on line 6-6 of Figure 1. Figure 60 7 is a horizontal, sectional view, corresponding substantially to the line 7-7 of Figure 1, showing the adjacent edges of the doors partly separated. Figure 8 is a detail perspective view illustrating the connection 65 between one of the horizontal framing members and one of the vertical framing members. Figure 9 is a perspective view of the outer margin of the right hand section of the closure as viewed from the interior of 70 the car. Figure 10 designates the portion of the closure shown in Figure 9 as viewed from the outside of the car. Figure 11 is a side elevation of a portion of the car showing my improvements in connection with an 75 alternative construction wherein the door closure is moved entirely to one side of the door opening. And Figure 12 is a horizontal sectional view taken on line 12-12 of Figure 11.

In said drawings, 10 denotes the vertical side wall of the car formed with the usual door opening in the side thereof, the car being provided with a channel side sill 11, floor boards 12, door posts 13-13, side top 80 members formed of angle 14 and plate 15, and the usual diagonal braces 16 connected to the top member by means of rivets and gusset plates 17. The floor boards throughout the width of the door opening are protected by means of threshold plate 18.

The closure for the door opening as shown in Figure 1 consists of two sections "A" and "B," each preferably formed of a metallic plate and movable in opposite directions to either side of the doorway. These door sections are slidably mounted on a horizontally disposed track 19 which pref-

erably consists of a bulb angle member secured to the side sill 11 and extending outwardly beyond the door posts 13-13 and longitudinally to either side thereof, the track 19 being cut out at 20 where it passes the door posts and welded thereto at 21 and 22.

The door sections, as shown in detail in Figure 5, have the bottoms thereof each reinforced by an angle-shaped member whereof the vertical leg 23 is secured to the door plate by means of countersunk rivets and the horizontal leg 24 in sliding engagement with the horizontal surface 25 of the track 19. The plate forming each section is bent outwardly to conform to the shape of the angle and thereafter extends downwardly and in the shape of a U, as shown in Figure 5, extending around the bulb 27 of the track 19, thus providing an interlocking seal joint therewith and furthermore providing a construction of great strength and rigidity for the lower margin of the door sections. The rear vertical margin of each door section is bent inwardly and formed U-shape as at 28 to conform substantially to the shape of the bulb 29 of the door post 13 and thus form an interlocking seal joint therewith. The door sections A and B are adapted to meet preferably centrally of the door opening and the meeting edges of the sections are adapted to overlap to fully close the door opening. In order to guard the door sections from deflection in a vertical plane the front edges thereof are in the form of beams of sufficient strength to resist bending of the closure. The front margin of door section A is channel shaped as indicated at 30 and the outer edge of the channel flange is rigidified by a U-shape bend 31. The outer corner of the channel-shaped portion 30 is flared to a limited extent as shown at 32 to facilitate interengagement between the respective door sections. The front edge of door section B is in the form of a Z, as shown at 33, and when the door sections are in closed position, the Z-shaped portion of this section is adapted to fit over the channel-shaped portion of the opposite door section. As shown in Figures 9 and 10, the lower portion of the Z-shaped margin of section B is formed pan-shaped by means of horizontal wall 34 and upwardly extending flange 35. This pan-shaped portion extends under and around the U-shaped margin 26 of the opposite door section and in this manner any leakage of lading which might seep through the crevices at the meeting of the respective door sections will be caught in this pan-shaped portion and choking of such material quickly result, thereby preventing leakage. The upper margin of each door section is reinforced

in a suitable manner and preferably by bending the main body of the plate outwardly and downwardly, forming a U-shaped section 36 which is preferably filled by a block of wood 37 to further strengthen the margin and prevent inward collapse of the outer flange of the U-shape. This upper margin 36 is disposed between flange 38 of Z-bar 39 which is secured to the top angle member 14 of the side framing and between the downwardly extending flange of the angle member 40 which is secured to the web of Z-bar 39. Downwardly extending flange 38 of Z-bar 39 acts as a weatherstrip to prevent the entry of rain inside the car and further serves to prevent outward movement of the closure from pressure of the lading thereon. In order to insure a weather-proof joint between the door sections adjacent the upper margin thereof, the depth of the Z-section 33 on door section B gradually decreases near the top thereof and the outer flange of the Z portion is welded at 41 to the lower edge of the U-shaped margin 36, thereby providing a downwardly sloping ridge 42 beneath which the channel-shaped portion 30 of door section A extends, the latter being notched or otherwise pressed to shape to fit under the aforesaid ridge.

The security thus afforded by the weatherproof overlapping joint between the two door sections is further augmented by means of an elongated sealing member 43 formed with a hook portion 44 adapted to engage the rigidified edge 31 of door section A. This sealing member 43 is vertically disposed and preferably formed to extend continuously along the joint between the sections A and B forming the closure. A series of hinge members 45 are rigidly secured to the sealing member 43 and are pivotally mounted at 46 on crank arms 47 which are rigidly keyed at 48 to vertically extending shaft 49 rotatably mounted in bearings 50 which are secured to door section B adjacent the front edge thereof. A lever 51 mounted on the shaft 49 in such a manner as to permit of vertical swinging movement on the shaft furnishes the means for effecting rotation of the said shaft and in cooperation with locking hasp 52, locking pin 53 and lock-plate 54, is adapted to lock and seal the doors relatively to each other and to the car structure as the hasp 52 passes through a slot in the lever 51 and pin 53 then inserted in a perforation in the hasp in the path of the lever, thereby preventing outward movement of the same. In order to prevent rain from entering in the crevice between the door section and the top of the sealing member and percolating to the interior of the car, the shedding ridge 42 is extended over the said crevice and formed with a beading 55.

In a car of this type where the lading is in direct contact with the closure, it will be appreciated that considerable difficulty would ordinarily be experienced in opening the closure with the load thereagainst. I have therefore provided novel leverage multiplying means for prying the door sections open a limited distance, and permitting the discharge of the greater portion of the load which is pressing against the closure to relieve the pressure against the closure to such an extent that further opening of the same is facilitated. The opening or starting mechanism, in its preferred form, is illustrated in Figure 1 and consists of a bracket 56 secured to door section A; a lever 57 pivoted to such bracket by means of pivot 58 at a point intermediate its ends and thus providing short and long lever arms; a sliding bolt 59 passing through guide 60 which is preferably formed integrally with bracket 56, said sliding bolt 59 being pivotally secured to the outer end of the short arm of lever 57 by means of pivot 61 and extended to engage the other door section where an abutment 62 is provided therefor. An additional guide 63 is preferably included to support and guide the outer end of the sliding bolt 59 thereby causing the same to move in a straight line, whereas the pivot 61 moves in an arcuate path. In order to compensate for such differential movement, the perforation for the pivot 61 is slotted as shown at 64. In this instance, the abutment 62 is, for purpose of economy, provided on the rear face of one of the shaft bearings 50 but it is to be understood that it might be formed as a separate member. A cam plate 65 is secured to door section A on which cam 66 is pivotally mounted and which engages the depending arm of the lever 57 for the purpose of maintaining the bolt 59 in a release position as the lever arm would normally hang in a vertical position due to its weight and move the bolt 59 in the path of the door opening where it would be liable to bending or be a source of danger to trainmen passing in and out of the car. The bracket 56 is provided at the rear thereof with a countersunk recess 67 in a wall thereof for the reception of the head of pivot 58, thereby permitting the assembling of bracket 56, lever 57 and sliding bolt 59 and riveting the same to the door section as a self-contained unit.

It will be seen that while the mechanism as described is efficacious for moving the door a short distance, its range of operation is limited and with certain kinds of lading it is desirable to be able to pry the door sections open throughout their entire range of movement and in order to accomplish this object, I have disposed a bracket

68 at the rear bottom corner of each door section, provided with a hole 69 and an abutment 70 at a short distance below the lower margin of the door closure. A lever or suitable operating bar 72 is adapted to engage the hole 69 or abutment 70 for the purpose of successively engaging a series of fulcrum locations on the car structure whereby the door section may be moved in either direction with a step by step operation of the said lever or operating bar. The fulcrum locations in the present instance consist of a series of perforations 71 disposed at short intervals in the horizontal wall of the track 19. To move the doors in an opening direction, the bar 72 is inserted through the hole 69 of the bracket with the end of the bar 72 engaging in one of the perforations 71 and the bar moved in the direction indicated by arrow 73 in Figure 1. Closing is effected by a reversal of the above movement except that instead of passing the operating bar through the hole 69 of the bracket it may bear directly on the abutment 70.

Suitable stiffeners such as shown at 74 are provided on each door section and are preferably formed to extend between the vertical margins thereof.

The opening of the door is effected as follows: Assuming that the parts are in position as shown in Figure 1, the locking pin 53 is removed from the hasp 52 and the lever 51 moved outwardly, thus rotating the shaft 49 until such time as the hook portion 44 of the sealing member 43 has moved outwardly a sufficient distance to clear the edge 31 of door section A, when the sealing member is then swung back against the door section B. The double joint provided by the crank arms 47 and rotary shaft 49, together with hinge members 45 enables the sealing member 43 to move bodily. The locking cam 66 is then moved out of the path of the lever 57 and the operator, by grasping the end of the lever, exerts pressure thereon in an opening direction, as indicated by arrow 75. This forces the sliding bolt 59 against door B, thereby forcing the door sections apart and permitting the discharge of lading. Any further opening of the closure may then be effected by fulcruming the bar 72 on the member 19 in the manner explained before.

To lock the door sections in closed position over the opening, the sections are moved relatively close to each other and the hook portion 44 of the sealing member 43 caused to engage the edge 31 of door section A as shown in Figure 7. The lever 51 is then rotated in the direction indicated by the arrow 76 thereby closing the toggle, forcing the closure sections into tight wedg-

ing engagement with each other and pulling the sealing member tightly over the joint between the sections.

In the arrangement illustrated in Figures 11 and 12, I have formed the single closure member so as to move entirely to one side of the door opening instead of in sections to either side thereof and have adapted the sealing mechanism to clamp and lock the closure directly to a portion of the car structure. In like manner the opening mechanism directly engages the car structure to move the closure in an opening direction. It will be understood that in this arrangement the upper, lower and rear edges of the closure are of the same construction as described in the preceding arrangement and the sealing member and operating mechanism are also of the same general character as described before.

In said arrangement, 110 denotes the side wall of the car, 111 the side sill, 112 floor boards, 113 rear door post, 114 front door post, 115 side top plate, 116 side framing, 117 side bottom member and 118 side door top cover. The front door post 114 extends outwardly beyond the rear post 113 and is preferably disposed in the same plane as the horizontal member 117. The door or closure member C is preferably formed of a steel plate reinforced by a horizontal stiffener 119 and the lower corner of the door is provided with bracket 120 formed with perforation 121 and abutment 122 for the purpose of moving the door in conjunction with the fulcrum locations 123 formed in member 117.

The front edge of the closure is reinforced by bending the plate in the form of a Z at 124 which portion is adapted to overlap the front door post 114, the latter preferably being formed of a bulb angle with the bulb 125 on the outstanding leg thereof. The closure is moved relatively toward the door post and locked thereto by means of sealing plate 126 formed with hook portion 127 adapted to engage over bulb 125 of the door post 114. The sealing member is hingedly mounted on the closure as before by means of hinge members 128, hinge pivots 129, and crank arms 130 rigidly secured to shaft 131 which is rotatably mounted in brackets 132 secured to the closure. Rotation of the shaft 131 is effected by lever 133 which is adapted to be locked to the bracket 134 on the closure by means of pin 135 passing through hasp 136.

The opening mechanism for the closure consists of bracket 137, lever 138 pivoted to the said bracket by means of pivot 139, and hook 140 formed with shank 141 passing loosely through guide 142 and connected to lever 138 by means of pivot 143. The hook 140 engages with a pivoted bar 144 pivotally

mounted on a bracket 145 by means of pivot 146 and secured directly to the car structure. The pivoted member 144 is maintained in operative relation for the opening operation of the door by abutting wall 147 on the bracket 145 but is free to move rearwardly out of the path of the door as indicated by dotted lines in Figure 12.

From the construction herein outlined, it will be readily seen that I have provided a closure for grain cars wherein the weight of the door resting on the bottom member forms an efficient seal against the escape of the lading and furthermore the outward thrust of the lading against the inner face of the closure forces the inner surfaces of the margins of the closure outwardly against the flanges fixed to the car thereby effectively preventing leakage of the lading and the entry of rain or water. In addition, the closure is so constructed that no part thereof may be removed or any part thereof pried open thereby preventing unauthorized removal of the contents of the car.

While I have shown and described what I now consider the preferred embodiment of my improvement, I am aware that changes and modifications may be made in the details of construction and arrangement of the parts without departing from the spirit of the invention and all changes and modifications are contemplated that come within the scope of the claims appended hereto.

I claim:

1. In a railway car, the combination with a door opening formed in a vertical wall thereof, of a closure for the said opening; and a track on which said closure is adapted to slide, said track having a depending flange along its outer edge, and the closure having a bent edge engaging therearound, and providing bearing surfaces.

2. In a railway car, the combination with a door opening in a vertical wall thereof; of a closure for the said opening; and a track secured to the car below the closure and adapted to slidably support the same on the car structure, said track having a depending flange along its outer edge,—the lower edge of the closure being formed in the shape of a U and engageable with the inner surface of the aforesaid depending flange, and providing bearing surfaces.

3. In a railway car, the combination with a door opening in a vertical wall thereof; of a track secured to the car below the door, said track having a horizontally extending surface and a depending flange; a closure for the aforesaid opening; an angle reinforcing member secured adjacent the lower margin of the closure, said angle member having one leg secured to the closure and the other leg in sliding engagement with the aforesaid horizontally extending surface of the

track; and a U-shaped portion on the closure engaging the depending flange of the track, whereby outward movement of the closure is restrained.

5. 4. In a railway car, having an opening in a vertical wall thereof, the combination with a bulb angle member fixed relatively to the car structure and disposed adjacent the bottom of the opening with the bulb portion 10 on the outstanding leg thereof and extending downwardly; of a door slidably mounted on the aforesaid bulb angle member and having the lower marginal edge thereof bent U-shape and extended around the bulb portion 15 of the angle member.

5. In a railway car, the combination with a door opening formed in a vertical wall thereof; of a slidably mounted closure for the said opening formed of metal plate 20 and having the upper margin thereof reinforced by bending the plate outwardly into U-shape and having the respective lateral margins and the lower margin reinforced by bending the main body of the 25 plate inwardly into a U-shape.

6. In a railway car, the combination with a door opening in a wall thereof; of vertically disposed door posts fixed relatively to the car structure adjacent the ends of 30 said opening and presenting oppositely disposed external flanges; a member fixed relatively to the car structure adjacent the bottom of the door opening and having a downwardly extending flange, the said 35 member extending outwardly beyond the plane of the door posts; and a closure for the door opening supported by the member adjacent the bottom of the door opening and adapted to slide thereon and across the 40 said opening, said closure having U-shaped margins engaging over and around the aforesaid flanges formed on the door posts and bottom member respectively.

7. In a railway car, the combination with 45 a door opening in the side thereof; of door posts formed of bulb angles disposed adjacent the said opening; a bulb angle member disposed adjacent the bottom of the said doorway and projecting outwardly 50 beyond the door posts and to either side thereof, the said bottom bulb angle member being cut away to pass the door posts; and a welded connection between the bottom bulb angle and door posts.

55. 8. In a railway car, the combination with an opening; of sliding doors for covering said opening, one of such doors having a channel-shaped marginal edge and the other door having a Z-shaped marginal edge 60 adapted to overlap the aforesaid channel-shaped edge of the other door.

9. In a railway car, the combination with an opening; of sliding doors movable in opposite directions and adapted to meet 65 and cover said opening, the meeting mar-

gins of said doors constituting vertical beams arranged to overlap each other, the outer beam having the lower portion thereof in the form of a pan within which the lower portion of the beam on the companion 70 door is adapted to be enclosed.

10. In a railway car, the combination with a door opening, of a closure adapted to close the said opening, the said closure being composed of relatively slidable sections having the bottom margins thereof bent inwardly into a U-shape to co-operate with a flange provided on the car structure, the said sections meeting in an overlapping relation with the U-shape margin 75 30 on the outer of such sections overlapping the U-shape margin on the other of the sections.

11. In a railway car, the combination with an opening; of oppositely movable 85 sliding doors adapted to overlap when in closed position; a vertical beam on the margin of the outer door within which the inner door is adapted to extend, the said outer door having the upper portion thereof welded to the upper margin of the door to thereby form a weather-proof hood extending over the crevices formed at the junction of said doors.

12. In a railway car, the combination 90 with an opening; of a closure for the said opening formed of two sections slidable relatively to each other; means carried by one of the sections to force the said sections apart; and means carried by the other 100 section to draw the said sections together.

13. In a railway car, the combination with an opening; of a slidably mounted door for such opening; and mechanism for moving the said door, said mechanism including a lever pivoted to the door with the pivot thereof disposed intermediately of the ends of the lever, a sliding bolt connected to one arm of the lever and extending beyond the door for engagement with 110 an abutment independent of the said door, the said bolt being adapted to be moved by movement of the opposite arm of the lever.

14. In a railway car having sliding doors, mechanism for moving the doors including, a bracket secured to one door, a lever pivoted intermediate its ends to the bracket, a sliding bolt connected to one end of the lever and adapted to engage a member on the other door, the opposite end of the lever 120 being adapted to be engaged for moving the door; and means for locking the lever relatively to the door.

15. In a railway car having an opening in a wall thereof, the combination with a 125 horizontally extending member disposed adjacent the bottom of the opening; of a door movable on the said member; and means for moving the door on the said member, the said means comprising a 130

- bracket secured to the door adapted to have a lever fulcrum thereon, and a series of perforations disposed in the said horizontally extending member for the purpose of successively fulcruming the lever on the car structure and thereby effect a step by step movement of the door.
16. In a railway car, the combination with a door opening; of two doors adapted to slide towards each other for the purpose of closing said opening; and means mounted on one door and adapted to swing at an angle to the plane thereof over the edge of the other of said doors for moving the doors towards each other.
17. In a railway car, the combination with an opening; of a closure for the said opening formed of two sections slideable relatively to each other; and toggle mechanism carried by one of the sections and adapted to engage the other of said sections.
18. In a railway car, the combination with a door opening, of two doors slideable towards each other for closing said opening; and a movable sealing member covering the meeting edges of the doors.
19. In a railway car, the combination with a door opening; of two doors slideable towards each other for closing said opening; a sealing member hingedly secured to one door and having a hook portion adapted to engage the other door; and means for drawing the doors together through the medium of the said sealing member.
20. In a railway car, the combination with a door opening; of two doors slideable towards each other for closing said opening; toggle mechanism mounted on one door and carrying a sealing member adapted to extend over and engage the other door; and means whereby closure of the toggle mechanism operates to move the doors towards each other and lock the doors relatively to each other.
21. In a railway car, the combination with an opening; of a closure for the said opening formed of two sections slideable relatively to each other; a vertically disposed rotatable shaft carried by one of the sections, a crank arm rigidly secured to said shaft; and a hook-shaped member pivoted to the said crank arm and adapted to have engagement with the other of said doors.
22. In a railway car, the combination with an opening; of a slideable closure member for the said opening; a vertically disposed rotatable shaft carried by the closure; a crank arm rigidly secured to the said shaft; and a hook-shaped member pivotally secured to the crank arm and adapted to engage a member independent of said closure member whereby rotation of the shaft will effect movement of said closure member in a closing direction.
23. In a railway car, the combination with an opening; of a closure for the said opening formed of two relatively slideable sections; a vertically disposed shaft carried by one of the sections; crank arms rigidly secured to the said shaft; a member hingedly mounted on the crank arms and adapted to engage the other section; a lever for effecting rotation of the shaft, said lever being pivotally mounted on the shaft and having motion in a vertical plane; and means for locking the lever in the place of rotation of the shaft.
24. In a railway car, the combination with a door opening; of door posts fixed relatively to the car and presenting oppositely disposed external flanges; of a closure for said opening formed of two doors each having a U-shaped margin engaging the aforesaid flanges of the door posts and means for forcing the doors towards each other and into tight engagement with the door posts.
25. In a railway car, the combination with an opening; of a closure for the said opening formed of two relatively slideable sections, adapted to meet centrally of the opening in an overlapping relation; a sealing member extending over the joint between the two sections comprising the closure, the said sealing member having hinge members secured thereto pivotally mounted on cranks rigidly secured to a shaft, said shaft being pivotally mounted in bearings rigidly secured to one of the sections; a lever secured to the shaft; and means for locking the lever in predetermined position.
26. In a railway car, the combination with an opening; of a closure therefor; a member mounted independently of said closure; a rotatable shaft carried by said closure; an arm secured to said shaft; and a hooked member secured to the crank arm and adapted to engage and over-lie the said independently mounted member for the purpose of sealing the joint therebetween and the closure.
27. In a railway car, the combination with an opening; of a closure therefor; a member mounted independently of said closure; a sealing member movably mounted on said closure and adapted to engage and over-lie the independent member; and means for locking said sealing member in position.
28. In a railway car, the combination with an opening; of a closure therefor; a member mounted independently of said closure; a sealing member movably mounted on said closure and adapted to engage and overlie the said independent member; and means for moving said closure member with respect to said independent member through the medium of said sealing member.
29. In a railway car having an opening, the combination with a sliding door adapted to move across said opening; of engaging means associated with said car, and engaging means associated with said door, one of

said means providing a plurality of fulcrum locations, said engaging means being disposed in a substantially vertical plane, and adapted to removably accommodate an actuating member, operation of which effects movement of said door.

In witness that I claim the foregoing I

have hereunto subscribed my name this 15th day of January, 1923.

ARGYLE CAMPBELL.
